UNITED STATES PATENT OFFICE

115,192

DESIGN FOR A LAUNDRY WASHER

Harold L. Belding, Northampton, Mass., assignor
to Henrici Laundry Machinery Company, Bos-
ton, Mass., a corporation of Massachusetts

Application August 19, 1938, Serial No. 79,441

Term of patent 14 years

To all whom it may concern:

Be it known that I, Harold L. Belding, a citizen of the United States of America, residing at 27 High Street, Northampton, in the county of Hampshire and Commonwealth of Massachusetts, have invented a new, original, and ornamental Design for a Laundry Washer, of which the following is a specification, reference being had to the accompanying drawing, forming a part thereof.

The figure is a view in perspective of a laundry washer embodying my new design.

The side and end of the washer not shown in the drawing are substantially plain.

I claim:

The ornamental design for a laundry washer, substantially as shown and described.

HAROLD L. BELDING.
